WINDOW REGULATOR

Alan D. Brundage, Detroit, Mich., assignor to
 F. L. Jacobs Co., Detroit, Mich., a corporation
 of Michigan

Application August 2, 1945, Serial No. 608,403

1 Claim. (Cl. 268—124)

1
 This invention relates generally to motor vehicles and more particularly to a window operating mechanism for raising and lowering windows in a vehicle.

An object of the present invention is to provide a motor driven window regulator which is of simple and inexpensive construction, yet which is reliable and easy to operate.

Another object of the invention is to provide a motor driven window regulator which embodies a sub-assembly that may be completed as a unit and then quickly attached to the window glass and to the door panel, so as to facilitate vehicle assembly operations.

A further object of the invention is to provide an improved type of window regulator in which means are provided to guide the window in a straight line movement and to prevent binding of the window during its reciprocation. This construction also supports the window during its opening and closing movements.

A still further object of the invention is to provide an improved type of window regulator in which the sliding glass is supported at two relatively widely spaced points upon a pair of swinging arms which carry meshing gear teeth to insure simultaneous swinging movement of the arms in opposite directions and to guide the glass in a straight line direction during its reciprocation. The invention also contemplates counterbalancing means to assist in raising the window, and means for adjusting the relative positions of the swinging arms to compensate for misalignments.

The invention is applied to a window operating mechanism of the type having a structure similar to that which is described and claimed in my co-pending application, Serial No. 561,521, filed November 2, 1944, now abandoned.

Other objects and advantages of the present invention will be made more apparent as this description proceeds particularly when considered in connection with the accompanying drawings, wherein:

Fig. 1 illustrates in elevation a window operating mechanism constructed according to one form of the invention;

Fig. 2 is a vertical cross-sectional view taken substantially on the plane indicated by the line 2—2 of Fig. 1;

Fig. 3 is an enlarged cross-sectional view taken substantially on the plane indicated by the line 3—3 of Fig. 1; and

Fig. 4 is an enlarged cross-sectional view taken substantially on the plane indicated by the line 4—4 of Fig. 1.

2
 Referring now to the drawings, and particularly to Figs. 1 and 2, the reference character 10 indicates a door of a motor vehicle having an inner panel 11 and an outer panel 12. The panels 11 and 12 are separated at their upper ends to provide a space 14 through which a vertically reciprocable window 15 is movable. The lower edge of the window glass 15 is seated in a metal channel 16 having a sealing strip 17 therein for holding the glass.

The mechanism for raising and lowering the window 15 comprises an elongated bracket plate 18 having a base portion 19 adapted to lie against the inner side of panel 11, and which is secured thereto by a plurality of distributed screws 20. The base portion 19 of the plate has inwardly pressed projections 21 for receiving the screws 20, which are inserted from the outer side of the panel.

Along its vertical side edges, the plate 18 has inwardly turned flanges 22 and 23 which reinforce and strengthen the plate, and these flanges are substantially deepened as indicated at 24 and 25. At their lower ends the wider portions 24 and 25 of the flanges are turned outwardly to form cross flanges 26 and 27. To further strengthen the plate, it is formed with vertically extending pressed out ribs 28 and 29 adjacent opposite side edges of the plate. The plate generally is reduced in width progressively toward its upper end. Openings 30 and 31 reduce its weight and lessen the amount of metal required.

An electric motor 32 is secured to the cross flanges 26 and 27 of the plate 18 by means of bolts 33 and nuts 34. A disk 35, preferably constructed of rubber, is provided between the upper end of the motor casing and the cross flanges 26 and 27 to avoid vibrational noise, and at the same time provide a cushioned support for the motor.

A long vertically arranged shaft 36 is employed in place of the usual motor shaft, and this long shaft at its lower end is journaled in a spherical bearing arranged in a spherical socket as shown at 37 in Fig. 2, so as to take care of slight misalignments. Shaft 36 is journaled at the upper end of the motor in a bearing 38 on the motor casing, which may also be of the self-aligning type if desired. Above the motor, shaft 36 is formed with a screw or thread 39. As best seen in Fig. 3, the upper end 40 of the motor shaft is smaller and projects into a ball element 41. This ball element seats in a spherical shaped socket portion 42 formed in a U-shaped bracket element 43 which has its legs spot welded to the base 19 of the bracket plate 18. This construction pro-

vides a self-aligning bearing for the upper end of the shaft 36.

To move the window vertically, a nut 44 is provided on the screw 39. As best seen in Fig. 1, this nut is generally of inverted T-shape with the vertical leg threaded on the screw. Opposite ends of the cross portion of the nut are respectively connected to vertically disposed arms 45 and 46 in such a manner as to permit pivotal movement of the nut about a horizontal axis. The upper ends of the arms 45 and 46, as best shown in Fig. 4, are pivotally connected to legs 47 and 48 respectively of a U-shaped bracket 49. The pivotal connection in this instance comprises rivets 50. Movement of arms 45 and 46 about a horizontal axis is thus permitted. The base of the U-shaped bracket 49 is connected by screws 51 and 52 to a vertically depending leg 53 of a window attaching element 54. This element has a vertically disposed portion 55 welded to one side of the window channel 16 and a horizontal intermediate tongue 56 which is welded to the base of the channel.

As best seen in Figs. 1 and 2, a bracket 57 is secured to plate 18 near the lower end of the plate. Opposite ends 58 and 59 of the bracket fit against flanges 22 and 23, and the upturned flange 60 of the bracket is welded to the base 18 of the plate. A rubber cushioning block 61 is supported upon the bracket 57 and is provided with an aperture or slot 62 for receiving the shaft 36. The bracket 57 is likewise provided with a slot for this purpose. The rubber block is retained in position by the upturned edges 63 of the bracket, and serves to cushion the nut 44 at the lower end of its movement as well as limit such movement.

Channels 64 are provided for receiving the side edges of the glass as it moves downwardly into the door below the window opening. These channels are welded to the door 10.

It will be apparent from the foregoing that operation of the motor 32 raises and lowers the window 15 through the screw shaft 36, nut 44 and associated structure. As hereinafter described, means are provided for guiding the window during its reciprocation and insuring straight line movement thereof.

A pair of swinging arms 65 and 66 are pivotally mounted upon the plate 18 at equal distances on opposite sides of the vertically disposed screw shaft 36. Intermediate its ends rib 28 of the plate is enlarged to form a boss 67. A pivot pin 68 is mounted in boss 67 and has flats 69 to prevent rotation of the pin relative to the plate. Arm 65 is pivotally supported upon the pivot pin 68 and is held axially against the boss by any suitable means.

Rib 29 is also enlarged intermediate its ends to form a boss 70 which is elongated in a generally vertical direction. This boss is provided with an elongated arcuate slot 71 concentric with pivot pin 68. Extending through the slot is a pivot pin 72 which has one end threaded to receive a nut 73 to enable it to be clamped in any desired position in the slot, for a purpose to be more fully described hereinafter. Arm 66 is pivotally supported upon the pin 72.

Arms 65 and 66 are generally similar in construction, and are progressively tapered or decreased in width from their inner ends 74 to their outer ends 75. The inner ends of the arms terminate in arcuate portions concentric with the pivot pins 68 and 72 respectively and formed with peripheral gear teeth 76. The teeth on

arms 65 and 66 are constantly in mesh thus providing simultaneous coordinated swinging movement of the two arms about their respective pivot pins.

Depending from the lower edge of the metal channel 16 at the bottom of window 15 are a pair of laterally spaced guide members 77 and 78. The guide members are positioned equal distances on opposite sides of the vertical centerline of the window, and are provided with horizontally aligned elongated slots 79 and 80 respectively. The upper ends 75 of the swinging arms 65 and 66 carry studs 81 and 82 respectively, which are slidably received in the guide slots 79 and 80 respectively.

Fig. 1 illustrates the relative position of the parts of the window operating mechanism when the window is in its uppermost or closed position. It will be noted that in this position nut 44 is near the upper end of the screw shaft 36 and the swinging arms 65 and 66 are disposed generally upwardly with the studs 81 and 82 near the inner ends of slots 79 and 80 respectively. As the motor 32 is operated to rotate shaft 36 and lower the window, the studs carried at the outer ends of the arms 65 and 66 are moved outwardly in the slots in the guide members 77 and 78 respectively, and the arms are simultaneously swung about their pivot pins, the arm 65 moving in a counterclockwise direction and the arm 66 in a clockwise direction. It will be apparent that the arms cooperate with each other and with the guide members 77 and 78 to guide the window in a straight line direction during its opening and closing movements, thus preventing binding of the window in its channels and facilitating its operation.

Misalignment of the window 15 in the side channels 66 can be corrected by adjustment of the pivot pin 72 for the arm 66. This pin can be moved to any desired position in the arcuate slot 71 and clamped in its adjusted position by the nut 73. Inasmuch as the arcuate slot 71 is concentric with the pivot pin 68 for the arm 65, it will be seen that the gear teeth 76 on the two arms are maintained in proper meshing engagement regardless of the adjustment of pivot pin 72.

A coil spring 83 encircles pivot pin 68 and one end of the spring projects into an opening 84 in the pivot pin to positively connect this end to the pin. Since the pin 68 is non-rotatably mounted in plate 18, this end of the spring is effectively anchored. The opposite and outer end of the spring extends through an opening 85 in a bracket 86 carried by the arm 65. The arrangement of the spring is such that the spring unwinds when the window moves upwardly, and winds up when the window is lowered. During lowering of the window, the weight of the latter assists in winding the spring, thus reducing the load on the motor. When the window is raised, the spring counterbalances the weight of the window and assists in raising it.

From the foregoing description it should be evident that the means for raising and lowering the window is mounted on a bracket plate which may be easily and quickly installed as a unit simply by attaching the plate to the door panel by screws 20, fastening the U-shaped element 49 to the window by means of screws 51 and 52, and then positioning the pins 81 and 82 on the outer ends of the swinging arms in the slots 79 and 80 respectively in the guide members 77 and 78. Plate 18 has adequate strength for supporting the assembly yet can be inexpensively constructed.

from sheet metal. The motor driven shaft 36 rotates freely in self aligning bearings and operates the window by reciprocating nut 44. It will also be seen that the window is guided in a straight line direction by the arms 65 and 66 preventing tilting of the window and binding in the window channels. During lowering of the window, the arms 65 and 66 are rotated downwardly from the positions shown in Fig. 1 and when the window is completely lowered assume positions extending downwardly and outwardly from the pivot pins 68 and 72 respectively. Furthermore, means are provided for adjusting the position of one of the arms to compensate for initial misalignment of the window in its channels, and a counterbalancing spring is provided to reduce the load on the motor and facilitate the window raising operation.

Although I have shown and described certain embodiments of the invention, it will be understood that I do not wish to be limited to the exact construction shown and described, but that various changes and modifications may be made without departing from the spirit and scope of my invention as defined in the appended claim.

I claim:

A window operating mechanism for reciprocating a window mounted in a motor vehicle for vertical sliding movement, said mechanism comprising an elongated plate adapted to be secured to the vehicle and disposed in a vertical position, a motor mounted on the lower end of said plate, a generally vertically disposed screw shaft rotatably supported on said plate and operatively connected to said motor, a generally T-shaped nut 35

on said shaft movable therealong upon rotation of said shaft, a bracket having a pair of spaced legs, means for connecting said bracket to said window, a pair of spaced arm elements having corresponding ends pivotally connected to the cross portion of said T-shaped nut and having their opposite ends pivotally connected to said legs of said bracket, said arms constituting the sole means engaging said nut to prevent rotation thereof relative to said plate and window, a pair of swinging arms pivotally mounted at corresponding ends thereof on said plate on opposite sides of said screw shaft, said arms having gear sectors at said corresponding ends provided with intermeshing gear teeth arranged to provide simultaneous and equal swinging movements of said arms, and means for securing the outer ends of said arms to co-operating means carried by the window.
